United States Patent Office.

GEORGE J. ROBERTS, OF DAYTON, OHIO.

Letters Patent No. 82,556, dated September 29, 1868.

IMPROVEMENT IN CUT-OFFS FOR STEAM-ENGINES.

The Schedule referred to in these Letters Patent and making part of the same.

TO ALL WHOM IT MAY CONCERN:

Be it known that I, GEORGE J. ROBERTS, of Dayton, in the county of Montgomery, and State of Ohio, have invented a new and useful Improvement in Variable Cut-Off Steam-Valve Gear; and I do hereby declare that the following is a full, clear, and exact description thereof, which will enable those skilled in the art to make and use the same, reference being had to the accompanying drawings, forming part of this specification.

This invention consists in the devices for operating the induction-valves of a steam-engine, that the quantity of steam admitted into the cylinder shall depend upon the speed and be made variable, according to the power required.

Figure 1 is a sectional elevation of the valve-gear and valves, showing the general arrangement and method of operation.

Figure 2 is a vertical cross-section of fig. 1, through the line *x x*, showing the variable slide, and the arm by which it is moved, and the cam by which the valve is lifted.

Figure 3 is a horizontal section of fig. 2, through the line *y y*, showing the position of the valves and the induction and eduction-ports of the engine.

Similar letters of reference indicate corresponding parts.

A represents the cylinder of the engine.

B is the steam-chest.

C represents the valve-seats, which are cast with the chest.

D is the steam or induction-valve, and

E is the exhaust or eduction-valve.

F is the valve-chest cover.

g g are passages from the induction-chamber *h* to the cut-off valves D.

g' indicates the passage from the cut-off valve to the cylinder.

J represents the passage for the exhaust steam, which communicates with the exhaust-valves E.

The valves are lifted or opened by cams on the revolving shaft L.

M is the cam by which the cut-off valve is opened.

N is a slide or lifter, on which the cam M operates to lift the valve. The position of this slide N is varied by the speed of the engine. The amount of steam admitted to the cylinder is controlled by the hold which the cam in its revolution takes upon the slide N.

This slide is attached to the arm o on the shaft P, and the shaft P is connected with the governor of the engine by the arm q and connecting-rod R.

When the engine is running at a given or the required speed, the arm o will stand stationary, but if, from the throwing off or on of machinery, or from any other cause, the speed is either checked or accelerated, the arm o and slide N will be moved either toward or from the cam, thus giving the cam more or less hold of the slide, and consequently raising the valve more or less for the passage of steam to the cylinder.

For the purpose of insuring the closing of the valves, I apply spiral or other springs to the upper stems, as seen in the drawing at S.

The lower stems of the valves are marked t.

The exhaust-valves are raised by a cam on the revolving shaft L, and are held open during the whole length of the return-stroke, thus giving time for all the steam to escape from the cylinder before the piston arrives at the end.

Springs or rubber cushions may be placed so as to receive the "drop" of the valves and prevent injurious concussion.

A cut-off and an exhaust-valve are employed for each end of the cylinder, as seen in the drawing.

I claim as new, and desire to secure by Letters Patent—

1. The valves D E and the seats C C, constructed as herein set forth.

2. The arrangement of the slide N, cam m, arm o, shaft P, arm q, and connecting-rod R, as herein set forth.

GEO. J. ROBERTS.
